CAR-BOTTOM FURNACE

John C. Piper, Pittsburgh, Pa., assignor to Loftus Engineering Corporation, a corporation of Maryland

Application June 2, 1943, Serial No. 489,363

10 Claims. (Cl. 263—28)

1

This invention relates to annealing and heat treating furnaces, particularly to car-bottom or car-type furnaces. The invention lies in improvements in construction.

A furnace of the sort herein held in contemplation includes a furnace chamber constructed of refractory brickwork, externally reinforced and tied, by means of structural steel and tie-rods. The floor of the furnace, upon which the articles to be heat treated are borne, comprises the body of a car—a car that may be likened to a railway flat-car whose floor is constructed of refractory blocks. The car is adapted to travel on wheels or rollers between service position within the furnace chamber and loading and unloading position externally of such chamber. The front wall of the furnace is provided with a door which is opened and closed as need be, to permit of the said movement of the car into and out of the furnace chamber, and, alternately, to close the chamber for normal operation of the furnace.

When the furnace is in normal operation, fuel and air are projected in regulated quantities into the furnace chamber, maintaining combustion therein and heating to desired temperature the articles to be treated. The products of combustion find escape through suitable outgo ports that open through the walls of the furnace chamber, and communicate through suitable flues to a stack or other vent. After the work has been heated at regulated rate to the required temperature, the combustion within the furnace is retarded or interrupted, and the work allowed to cool through the desired cooling cycle.

As indicated above, the upper surface of the car body provides the floor of the furnace chamber, and means are provided for sealing the car body along its two sides and inner or back end to the two side walls and back wall of the furnace, while, as already mentioned, the door of the furnace seats upon the outer or front end of the car body. Thus, the body of the car is sealed to the furnace walls, to provide in effect an integral furnace chamber in which the desired conditions of combustion and thermal head may be established and maintained.

More particularly, my invention consists in improvements in the means for sealing the body of the car to the walls of the furnace.

In the accompanying drawings,

Fig. I is a fragmentary view in perspective of a car-bottom furnace including in exemplary way an embodiment of the invention.

Fig. II is a fragmentary view of the furnace

2

structure, as seen in horizontal section, on the plane II—II of Fig. III.

Fig. III is a fragmentary view of the furnace, as seen on the plane III—III of Fig. II.

5 Fig. IV is a fragmentary sectional view of the furnace structure, as seen on the plane IV—IV of Fig. III.

Referring to the drawings, it will be perceived that the walls of the furnace 2 and the body of 10 the car 3 are shown fragmentarily. Indeed, only the back wall 4 and one of the two side walls 5 of the furnace appear in the drawings, with the back end of the car shown fragmentarily. The front wall of the furnace, the door of the furnace, the burners, the waste gas flues, the mechanism for shifting the car into and out of the furnace, and such other conventional features of furnace construction as are not necessary to an understanding of the invention have been omitted from the drawings.

The means for sealing the car body to the furnace walls include, in accordance with usual practice, a steel channel 6 on each side of the car body, and this channel is filled with dry sand 25 60 or other suitable luting material. Mounted on each side wall 5 of the furnace is a member 7 that extends the length of the furnace, and this member includes a continuous flange portion 70 which, when the car is moved into the furnace chamber, 30 lodges in the sand in the corresponding channel 6 on the car, thus providing a seal between the side of the car body and the side wall of the furnace. The means for sealing the opposite side of the car to the opposite side wall of the furnace 35 are identical with the channel and flanged member last described, and thus it is that both sides of the car body are sealed to the furnace walls.

Means are provided for sealing the back or inner end of the car body to the back wall of 40 the furnace, and it will be understood that the door at the front of the furnace (not shown) engages the front end of the car, to complete the essential sealing of the car body to the furnace structure. The present invention is centered in 45 the means for sealing the back end of the car body to back wall of the furnace.

Referring to Fig. I, a box-like container 8, formed of steel plate or cast steel, is built into the back or rear end of the car body. More specifically, an iron or steel casting 9, integrated with the container side walls and arranged to form a top wall for the container, includes a horizontal flange 10 that is welded or otherwise united to the longitudinal beams 11 that provide the support for the refractory floor 12 of the car 3.

The casting 3 includes also a vertical flange 13 that laterally supports the terminal course of refractory blocks 14 of the floor of the car. These blocks 14 are severally formed with downwardly convergent passages 15, and the casting 3 is provided with orifices that severally register with the bottoms of such passages. These registered passages and orifices provide inlet openings that are accessible externally of the car body, for the charging of sand 68 or other luting material into the container 3. The container 3 and the several passages 15 comprise a hopper in which a relatively large supply of sand may be stored, whereby, regardless of the loss of sand that may be occasioned when the car is moved into and out of the furnace, a single charging of the container is adequate for a prolonged campaign of furnace operation.

The outermost wall of the container at the end of the car includes a slot 16 that extends the width of the car, and it is to be noted that, as viewed in Fig. III, the upper and lower edges 17 and 18, respectively, of this slot are so spaced apart that the plane defined by such edges is inclined to the horizontal at angle that is no greater than, and preferably is less than, the angle of repose of the sand confined in the container whereby the loss of sand through the slot is inhibited.

The back wall 4 of the furnace carries a blade 19 which extends transversely of the furnace chamber and projects inward from the face of the wall 4 at the elevation of the slot 16 in the container 3. When the car is moved into service position in the furnace, the otherwise free edge of the blade 19 enters the slot and embeds itself in the sand in the container, forming the desired seal between the end of the car and the end wall of the furnace. Preferably, the lower edge of the slot 16 is reinforced by means of an inclined flange 20, and this flange assists in guiding the edge of the plate 19 into the slot 16, in the event that the blade should become warped under the heat of the furnace. The upper edge 17 of the slot 16 is formed by the inner edge of a flange 21 that is inclined inwardly and downwardly from the slotted wall of the container.

As shown in Fig. III, the inner edge of flange 21 is positioned close to the upper surface of the blade 19 embedded in the sand in the container 3, and thus it is that, when the car 3 is withdrawn from the furnace and the blade emerges from the slot 16, the loss of sand from the container is minimized. Indeed, the flange 21 may be formed of an elastic material, such as heavy asbestos fabric, or other suitable material, and as such the flange will operate as a wiper flap upon the surface of the blade 19, to prevent loss of sand when the blade 19 emerges from the container.

To the end that the inner corners of the car body shall be perfectly sealed in the corners formed by the side and back walls of the furnace, the blade or flange portions 19 of the sealing members 7 carried by the furnace side walls are formed of increased vertical extent in the regions 70a (Fig. I), and are welded or otherwise secured and sealed, as at 22, to the body of the sealing blade 19. The sand-containing channels 6 on the sides of the car are sloped downward adjacent to the back end of the car (see dotted lines 6a in Figs I and III), to provide clearance for the vertically widened portions 70a of the side sealing members 7. The inner vertical wall of each sand-containing channel 6 is

slotted, as indicated at 6b in Fig. I, whereby the terminal portions of the blade 19 to which the flange portions 70a of the side sealing members are united, may enter the sand in the side channels 6 and thus provide a seal of uninterrupted continuity.

Manifestly, the construction and organization of the sealing means are such that, when the furnace door (not shown) is opened, the car may be moved into and out of the furnace chamber without the sealing means requiring any attention. The side sealing blade portions 70 simply cut as a knife through the sand contained in the channels 6 on the sides of the car, and the end blade 19 readily enters and leaves embedded position in the sand in the container 3. The advantages of the improvements herein described will be apparent to those skilled in the art.

From the foregoing specification, it will be seen that the furnace is constructed of two parts, the stationary furnace body 2 and the car 3 that is movable relatively thereto. The channels 6 and blades 70, carried respectively by the sides of the car and the side walls of the furnace, to provide the side sand seals, extend in parallelism with the direction of movement of the car 3 relatively to the furnace body 2, while the end sand seal formed by the hopper-like structure 3, 6, 16 and the plate element 19 extend transversely of such direction of relative movement of the furnace parts. It will be perceived that the horizontal wall of the container 3 below the opening or slot 16 provides a floor that receives and holds the sand into which the plate element 19 is in service embedded.

The walls of the container 3 may, as above noted, be formed of steel plate, this being for the reason that such walls are not directly exposed to the heat radiated by the incandescent walls 40 of the furnace chamber during the work-heating cycle of furnace operation. In the case of the blade or plate element 19, however, a portion of the blade 19 is exposed to the radiant heat of the furnace, and for this reason it is desirable, if not essential, to form such blade of cast iron or steel that possesses a much higher durability under heat than does steel plate. The cast body of the blade 19 is relatively rigid, while the steel body of the container 3 is relatively elastic or flexible. The elasticity or flexibility of the walls (particularly the slotted wall) of the container 3 is a desirable feature, since the body of the container is adapted to yield, in case the projecting edge of the blade 19 should engage the flange 20 when the car 3 is moved into service position in the furnace, and permit the slot 16 in the container to come to proper registry with the edge of the blade.

Various modifications in structure are permissible within the terms of the appended claims, without departing from the invention described.

I claim as my invention:

1. In a car-bottom furnace including a furnace chamber, a car movable into and from position of service within said chamber, and means for sealing the back end of the car body to the back wall of the chamber, the herein described improvement in such sealing means which comprises a sand container carried by and extending across the back end of the car body and having a slot opening in the sand-confining wall exposed at such end of the car body, and a sealing member secured to and extending from the back wall of the furnace chamber, the portion of said member extending from the furnace back wall being

adapted as the car is moved into service position within the furnace chamber to move horizontally into said slot and lodge in car-sealing position in the sand in said container.

2. In a car-bottom furnace including a furnace chamber, a car movable into and from position of service within said chamber, and means for sealing the back end of the car body to the back wall of the chamber, the herein described improvement in such sealing means which comprises a sand container having a slotted wall carried by and extending across the back end of the car body, and a blade sealed to and extending from the back wall of the furnace chamber, the otherwise free edge of said blade being adapted as the car is moved into service position within said chamber to move horizontally into said slot and embed itself in car-sealing position in the sand in said container.

3. In a car-bottom furnace including a furnace chamber, a car movable into and from position of service within said chamber, and means for sealing the back end of the car body to the back wall of the chamber, the herein described improvement in such sealing means which comprises a slotted sand container carried by and extending across the back end of the car body, and a sealing member secured to and extending from the back wall of the furnace chamber, the portion of said member extending from the furnace back wall being adapted as the car is moved into service position within the furnace to enter said slot and lodge in car-sealing position in the sand in the container, said container comprising a hopper having a charging inlet accessible externally of the car body.

4. In a car-bottom furnace including a furnace chamber, a car movable into and from position of service within said chamber, and means for sealing the back end of the car body to the back wall of the chamber, the herein described improvement in such sealing means which comprises a transversely slotted sand container carried by and extending across the back end of the car body, and a sealing member secured to and extending from the back wall of the furnace chamber, the portion of said member extending from the furnace back wall being adapted as the car is moved into service position within the furnace to enter said slot and lodge in car-sealing position in the sand in the container, the lower edge of the slot being horizontally offset from the upper edge of the slot, whereby the plane of the slot is inclined at an angle which is less than the angle of repose of the sand in said container.

5. In a car-bottom furnace including a furnace chamber, a car movable into and from position of service within the chamber, and means for sealing the car body to the side walls and back wall of such chamber, the herein described improvements in said sealing means comprising a channel containing sand extending along each side of the car, means carried by said side walls of the furnace chamber and adapted to enter the sand in said channels and seal the sides of the car body to the side walls of the furnace chamber, a sand container secured to and extending across the back end of said car and including in the rear wall thereof a slot extending the width of the car, and a sealing member secured to and extending from the back wall of the furnace chamber, the portion of said member extending from the furnace back wall being adapted as the car is shifted into service position within the furnace chamber to move horizontally into said slot

and lodge in car sealing position in the sand in the container to cooperate with the said sealing means at the sides of the car in sealing the car body to said walls of the furnace chamber.

6. The structure of claim 5, said sand container on the back end of the car comprising a hopper having a charging inlet accessible externally of the car body.

7. In a car-bottom furnace including a furnace chamber, a car movable into and from position of service within the chamber, and means for sealing the car body to the side walls and back wall of said chamber, said means including on each side of the car a longitudinally extending channel containing sand, a member including a vertical flange portion carried by and extending outward from each of the furnace side walls, each of said flange portions being adapted at its outer edge to lodge in the sand contained in the channel on the corresponding side of the car, whereby the two sides of the car body are sealed to the side walls of said furnace chamber, a sand container extending across the back end of said car, said container including in the rear wall thereof a transversely extending slot, a transverse blade secured to and extending horizontally from the back wall of the furnace chamber, the otherwise free edge of said blade being adapted as the car is moved into service position within said chamber to enter said slot and lodge in the sand in said container, to seal the back end of the car body to the back wall of the furnace chamber.

8. In a car-bottom furnace including a furnace chamber, a car movable into and from position of service within the chamber, and means for sealing the car body to the side walls and back wall of said chamber, said means including a longitudinally extending channel containing sand on each side of the car body, a member including a vertical flange portion carried by and extending outward from each side wall of the furnace chamber, each of said flange portions being adapted at its outer edge to lodge in the sand contained in the channel on the corresponding side of the car, whereby the two sides of the car body are sealed to the side walls of said furnace chamber, a sand container extending across the back end of said car, said container including in the rear wall thereof a transversely extending slot, a transverse blade secured to and extending horizontally from the back wall of the furnace chamber, the otherwise free edge of said blade being adapted as the car is moved into service position within said chamber to enter said slot and lodge in the sand in said container, to seal the back end of the car body to the back wall of the furnace chamber, said flange portions on the side walls of said chamber, embedded at their edges in the sand in the channels on the two sides of the car, making sealed engagement with the blade carried by the back wall of the furnace chamber.

9. In a furnace structure having relatively movable parts, cooperating means on said parts for establishing a sand seal that extends transversely of the direction of relative movement of the parts, said means comprising a projecting horizontal plate element on one of the parts, and a hopper-like structure containing sand on the other of said parts, said hopper-like structure having an opening into which the plate element of the other furnace part may project, there being means below said opening forming a bottom for the hopper to receive and hold the sand.

10. In a furnace having relatively movable inner and outer parts of substantially rectangu-

lar contour, and means for sealing the parts in telescopedically assembled position; the herein described invention in said means comprising sand containers extending along each of the two sides and across one end of the inner furnace part, vertical blades extending along the two sides of the outer furnace part and being removably embedded in the sand in the containers on the sides of the inner furnace part, said container on the end of the inner furnace part having an opening extending longitudinally between the containers on the opposite sides of said inner furnace part, and a horizontal blade member extending between and secured to said vertical blades of the outer furnace part and being movable through said opening into embedded position in the sand in the container on the end of the inner furnace part, said vertical and horizontal blades provid-

ing a continuous sealing blade around said sides and end of the outer furnace part.
